(57) **CLAIM**

The ornamental design for the faceplate for volatile actives dispenser, as shown and described.

DESCRIPTION

FIG. 1 is a front perspective view of the faceplate showing the new design.

FIG. 2 is a front view of the faceplate of FIG. 1.

FIG. 3 is a rear view of the faceplate of FIG. 1.

FIG. 4 is a top view of the faceplate of FIG. 1.

FIG. 5 is a bottom view of the faceplate of FIG. 1.

FIG. 6 is a left side view of the faceplate of FIG. 1; and,

FIG. 7 is a right side view of the faceplate of FIG. 1.

Detail shown by the dotted lines in FIG. 1 and FIG. 3-7 form no part of the design and are shown only for reference purposes.
